United States Patent

Des. 236,648
Patented Sept. 2, 1975

236,648

LAMP

Kenneth K. Knoepfle, 350 NE. 55th Terrace,
Miami, Fla. 33137

Filed Dec. 11, 1973, Ser. No. 423,662

Term of patent 7 years

Int. Cl. D26—05

U.S. Cl. D48—20 C

FIG. 4

FIG. 3

FIG. 5

FIG. 2

FIG. 1

FIG. 9

FIG. 8

FIG. 7

FIG. 6

FIG. 10

FIG. 1 is a front elevational view of a lamp showing my new design, the shade being omitted for purposes of disclosure;

FIG. 2 is a rear elevational view thereof;

FIG. 3 is an elevational view taken from the left of FIG. 1;

FIG. 4 is an elevational view taken from the right of FIG. 1;

FIG. 5 is a top plan view thereof;

FIG. 6 is a front elevational view of the complete lamp of my new design;

FIG. 7 is a rear elevational view thereof;

FIG. 8 is an elevational view taken from the left of FIG. 6;

FIG. 9 is an elevational view taken from the right of FIG. 6; and

FIG. 10 is a top plan view thereof.

I claim:

The ornamental design for a lamp, as shown and described.
